Application filed April 21, 1893. Serial No. 471,347. Term of patent 7 years.

To all whom it may concern:

Be it known that I, CHARLES WEINBERG, a citizen of the United States, residing at the city and State of New York, have invented a new Design for Gimp, of which the following is a specification.

The edge portions or stripes of my gimp are of ordinary appearance.

The leading feature of my design for gimp relates to the design of the central portion of the gimp which consists of a series of raised cords having the appearance of a chain.

My design for a gimp is shown in the accompanying drawing.

15 The edge stripes of longitudinal and transverse cords at a. a. and the scalloped edge b. are usual in gimps.

The design of the central portion of the gimp consists of the plain stripes c. c. and the stripes d. d. e. e. which are of alternating 20 raised cords in pairs having the general appearance of a chain.

I claim—

The design for a gimp as shown and described.
